UNITED STATES PATENT OFFICE.

SIMON W. WARDWELL, OF PROVIDENCE, RHODE ISLAND, ASSIGNOR TO
UNIVERSAL WINDING COMPANY, OF PORTLAND, MAINE, A CORPO-
RATION OF MAINE.

BOBBIN-HOLDER.

No. 829,306.

Specification of Letters Patent.

Patented Aug. 21, 1906.

Application filed June 13, 1905. Serial No. 265,048.

To all whom it may concern:

Be it known that I, SIMON W. WARDWELL, a citizen of the United States, residing at Providence, in the county of Providence and 5 State of Rhode Island, have invented new and useful Improvements in Bobbin-Holders, of which the following is a specification.

My invention relates to improvements in bobbin-holders or supply-spindles for supporting bobbins delivering yarn to winding or other machines, the object of my improvement being to facilitate the placing of the bobbin on its spindle and the removing or doffing of the empty tube.

15 My invention is fully set forth in the following specification, illustrated by the accompanying drawings, in which—

Figure 1 is a side elevation of the bobbin-holder, showing the bobbin in position for delivering the yarn; Fig. 2, a front elevation of 20 the same; Fig. 3, a side elevation showing the position the spindle assumes when the bobbin-tube is removed.

My invention consists, in brief, of a tilting 25 supply-spindle, which when tilted to remove an empty tube remains in this position until a full bobbin is supplied, when it is automatically returned to its normal position.

In the drawings, *a* represents the supply- 30 spindle adapted to fit the bore of the bobbin-tube *x*, which may be of any of the well-known forms as generally manufactured of wood. The spindle *a* is supported in a tilting bracket *b* and held by the set-screw *b*. The bracket *b* is preferably formed with two wings *c* and *d*, bored to receive the rod *e*, on 35 which the bracket turns, a series of brackets being generally arranged on the rod, with the latter supported in some convenient location on the machine. A collar *f*, adapted to enter 40 between the wings *c* and *d*, is likewise bored to receive the rod *e* and is secured to the rod by any suitable means, thus serving to locate and retain the bracket *b* longitudinally on the rod. I prefer to use the split collar *f*, as 45 shown, fastened by a binder-screw *g*, which clamps the collar tightly on the rod. The collar *f* is formed with a lug *h*, which engages the under side of the bracket *b* to limit the 50 turning of the bracket on the rod *e*, thus maintaining the spindle normally in its upright position. The spindle *a* is positioned

beneath the tension device of the machine, which is here represented as of a usual form by dash-lines at *i*, and it is generally required 55 to have the top of the spindle closely adjacent the tensions. If the supply-bobbin were located at too great a distance from the tensions, in unwinding the yarn would fly out and balloon, and it is a well-known fact that 60 excessive ballooning of the yarn causes added resistance to delivery. To prevent this, it is advantageous to have the supply-bobbin close to the tensions; but it will be seen that in order that the bobbin may pass the tension 65 device in placing it on or taking it off the spindle the latter must be adapted to tilt, as shown in Fig. 3. Tilting supply-spindles are well known in the art, and other means besides those just described might be employed 70 for providing this feature of the present device.

The novel feature of the invention consists in means whereby the presence of the bobbin upon its spindle insures the retention of the 75 latter in its normal operative position, while the removal of the bobbin insures that the spindle be retained in a different position, which facilitates said removal and also the application of a new bobbin.

The essential element of the device is a catch member *j*, preferably formed of a sheet-metal piece with a central aperture, through which the spindle passes. The member *j* is crimped or formed with a bend at *k*, which 85 portion rests on the top of the bracket *b*, presenting a rocker-bearing, the aperture in the member having play enough about the spindle to allow the member to tilt or rock. The catch or lock is formed by bending down the 90 end of a projection of the member at *l*, and this catch is adapted to engage a similar detent *m*, formed in a projection or lug on the collar *f*. Two lugs *j*² and *j*³ are formed on the member *j* by bending down narrow strips 95 of the metal, and these lugs project downward between the wings *c* and *d* of the bracket *b* to prevent the member *j* from turning, so that the catch *l* is maintained in its appropriate relation to the detent *m*. The 100 weight of the bracket *b* and spindle *a* tends to maintain the spindle normally upright with the bracket resting on the lug *h*, as shown in Fig. 1, this being its position when

the tube or bobbin is in place; but when the spindle is tilted, as shown in Fig. 3, and the bobbin drawn off the member *j* is released and the force of gravity acting on the heavier end 5 of the member *j* carries the catch *l* into engagement with the detent *m*, so that the spindle is then held in its tilted position.

In practice the operation of my device is as follows: With the spindle *a* in the position 10 shown in Fig. 3 the bobbin *X* is simply dropped onto the spindle and the head or bottom end of the tube *x* strikes the uplifted end *n* of the member *j*. The weight of the bobbin acting on the end *n* of the member *j* 15 tilts the latter and raises the catch *l* from the detent *m*, releasing the bracket and allowing it to drop into position against the lug *h*. The bobbin is now ready to deliver to the tension device *i*, as shown in Fig. 1. After 20 the yarn on the bobbin is exhausted the empty tube is drawn off, and this necessitates the tilting of the spindle, so that the catch *l* engages the detent *m*. After the tube is removed the spindle remains in this 25 convenient position, so that a new bobbin can be readily supplied. The instant the fresh bobbin reaches its seat on the spindle the catch *l* is released, and the spindle is automatically returned to its vertical position.

30 It will be seen that with my device the placing of the bobbin and the doffing of the empty tube are greatly facilitated. The operator need only use one hand, leaving the other free to thread the yarn in the tensions 35 or otherwise manipulate it, while with other devices it has always been necessary to tilt the spindle with one hand and place the bobbin with the other, using both hands at the same time. It will be evident that a great 40 saving of time and pains is accomplished by the use of my device, and its operation is most convenient.

Other means might be used for retaining the spindle in its tilted position and for releasing it when the bobbin is placed in position 45 without departing from the spirit of this invention. Therefore I do not limit myself to the precise structure and arrangement here shown; but

50 What I claim is—

1. The combination with a tilting bobbin-holder, of means to retain the holder in its tilted position, said means adapted to release the holder upon the application of a 55 bobbin.

2. The combination with a tilting supply-spindle, of a catch to maintain the spindle in its tilted position, said catch adapted to release the spindle upon the application of a 60 bobbin.

3. The combination in a bobbin-holder, of a spindle for the bobbin, a tilting bracket supporting the spindle normally in a vertical position, and means to automatically main-

tain the spindle in its tilted position upon the 65 withdrawal of the bobbin, said means adapted to release the spindle upon the application of a new bobbin.

4. The combination in a bobbin-holder, and with a tension device of a supply-spindle 70 located below and closely adjacent the tension device, means to support the spindle normally pointing toward the tension device and to allow it to tilt beyond said device, and means to retain the spindle in its tilted position, said means engaged by the bobbin to release the spindle to allow its return to the 75 normal position.

5. The combination in a bobbin-holder with a normally vertical, tilting spindle, of 80 means to retain the spindle in its tilted position, said means adapted to release the spindle upon the application of a bobbin to allow its return to normal position.

6. The combination in a bobbin-holder 85 with a spindle, of a tilting bracket supporting the spindle, a stop to limit the movement of the bracket to maintain the spindle in its delivery position, and a catch member adapted to retain the bracket in its tilted position and 90 to release the bracket upon the application of a bobbin.

7. The combination in a bobbin-holder with a tilting spindle supported to be maintained by gravity in its normal delivery position, of means to retain the spindle in its tilted position, said means adapted to be released by engagement of the bobbin to allow the return of the spindle to its normal position. 95

8. The combination of a supply-spindle, a bracket to support the spindle, a rod on which the bracket is pivoted, a collar to retain the bracket longitudinally on the rod, formed with a lug to limit the turning of the 105 bracket and also having a detent, and a catch member on the bracket adapted to engage the detent on the collar when the bracket is tilted, substantially as shown and described.

9. The combination of a supply-spindle *a*, 110 a bracket *b* for supporting the spindle formed with two wings *c* and *d* having alining bores, a rod *e* extending through the bores to support the bracket, a collar *f* fastened to the rod between the wings of the bracket, formed 115 with a lug *h* to limit the turning of the bracket and a detent *m*, and a catch member *j'* formed of sheet metal with an aperture through which the spindle passes, crimped at *k* to form a rocker bearing on the bracket and having a catch *l* to engage the detent *m* and two lugs *j*² and *j*³ extending between the wings of the bracket *b* to retain the member *j* in position on the bracket, substantially as 120 shown and described.

10. The combination in a tilting bobbin-holder of a catch member to retain the holder in its tilted position and formed with 125

a portion adapted to be engaged by the bobbin to release the catch.

11. A bobbin-holder supported to swing automatically to its normal operative position, combined with means controlled by the bobbin to retain the holder out of said position when the bobbin is not in place.

In testimony whereof I have signed my name to this specification in the presence of two subscribing witnesses.

SIMON W. WARDWELL.
